ATTACHMENT PLUG

Albert E. Grant, New York, N. Y., assignor, by
mesne assignments, to Merwin F. Ashley, Bos-
ton, Mass.

Application October 2, 1936, Serial No. 103,755
Renewed October 26, 1938

4 Claims. (Cl. 173—361)

My invention relates to attachment plugs of the type commonly known as "end plugs" or "connec-
tor caps" which are carried on the ends of extension
cords used for conducting current from a
standard supply outlet to various types of elec-
trically operated equipment. More particularly,
the present invention is an improvement in plugs
constructed in accordance with the principles
taught in United States Patent No. 2,043,851 is-
10 sued to Samuel W. Vanderbeek and myself, joint-
ly, on June 9, 1936.

The prior patent teaches a construction in
which rigid contact blades are resiliently mounted
in a housing from which they divergently extend,
15 the outer end portions of the blades being spaced
to engage socket openings in a standard conven-
ience outlet or receptacle, so that when the blades
are coupled in such outlet or receptacle they will
be drawn into substantial alignment and exert a
constant resilient pressure against contacts car-
ried in the receptacle, thereby obtaining firm me-
chanical connection and good electrical contact.

A principal object of my present invention is to
provide an improved end plug of this character
25 requiring fewer parts and designed for low cost
production. Another object is to provide an im-
proved structure of this type in which the resil-
ient means is formed integral with the cap or
housing member. A further object is to provide
30 a novel and inexpensive end plug having a one-
piece housing in which the end portions of the
extension cord wires are completely housed and
securely and permanently connected to the con-
tact blades. Other and further objects will ap-
35 pear from the following specification.

Referring to the drawing which forms a part of
this specification:

Figure 1 is a front elevational view of an end
40 plug embodying my invention, and

Figure 2 is a side elevation thereof.

Figure 3 is a vertical sectional view taken on
line 3—3 of Figure 2 and illustrates the spacing of
the outer ends of the blades in relation to the
socket openings of a standard receptacle or con-
45 venience outlet, the outlet or receptacle being in-
dicated in broken lines.

Figure 4 is a front elevational view showing the
disposition of the contact blades when coupled in
a standard convenience outlet or receptacle.

Figure 5 is a perspective view of one of the con-
tact blades.

In carrying out my improvement, I provide a
housing or cap member 10 of resilient insulating
material, such as a tough resilient rubber com-
position. The housing is molded or otherwise

formed to provide wire passages 15, 16 and 17 and
blade pockets or recesses 18—18. The housing is
preferably of the elongated shape illustrated to
afford convenient exterior gripping surfaces, and
the upper portion 11 thereof is reduced in diam-
eter to form a long and relatively slender neck
5 which affords flexible and resilient protection for
a substantial length of the extension cord 20 and
obviates any necessity for a separate guard to
protect the cord insulation.

As shown, the passage 15 is formed to receive
the end portion of the extension cord and extends
into communication with the branch passages 16
and 17. The branch passages communicate with
the respective blade pockets and closely accom-
modate end portions of the separate cord wires
21—22 which extend into the pockets and are
connected to the contact blades 25. The blade
pockets 18 are straight, deep slots which con-
verge inwardly from the face of the housing on 20
opposite sides of the passage 15, the face of the
housing being otherwise closed and continuous.

It will be noted that the branch passages of
this construction divide the separate wires of the
cord and maintain them spread in insulated rela-
25 tion to each other, so that if the usual wire in-
sulation becomes drawn back by reason of strain
on the cord, or peels, or is effected by any other
cause, the wires will nevertheless be held apart
in insulated relation by the passage walls. 30

The rigid contact blades 25 carried in the re-
spective blade pockets extend at divergent angles
from the face of the housing, the extreme outer
end portions 26 of the blades being bent or flanged
whereby they are disposed at reverse angles to 35
engage against the outer walls of the socket open-
ings 31—31 of a standard receptacle 30. Near
the outer end of each blade and adjacent the bend
therein the blade is perforate to engage with the
usual protuberance formed on the receptacle con- 40
tact members 32—32.

The blades may be of the usual thickness of
blades in devices of this kind but are preferably
stamped from thinner conducting metal of high
quality and embossed, as shown, intermediate 45
their margins over the greater portion of their
contact areas to render them rigid, all as taught
in my pending application Serial No. 87,879 filed
June 29, 1936.

The inner end of each blade is bifurcated or 50
notched at 27, the notch defining a pair of legs
28—28, the extreme end portions of which are
angularly bent to form dull prongs 28'—28'
adapted to engage the resilient inner walls of
the blade pockets without tearing them and

thereby prevent withdrawal of the blades from the pockets. As best illustrated in Figure 5, the inner edges of the legs 28—28 of each blade are curved convexly and converge gradually and sharply so that they will tightly grip the wire wedged and compressed between them in the notch 27. In the pocketed portions of each blade below the notch, a wire receiving aperture is formed at 29 and uninsulated end portions of the wires are threaded thru the apertures and extend thru the notched portions of the blades, substantially as illustrated in Figure 3.

To assemble the plug on the end of an extension cord, the insulation is removed from the end of the cord to expose portions of the wires. The cord is then inserted thru the wire passage 15 and the wires are passed out thru the respective branch passages and the pockets 18. The uninsulated ends of the wires are then threaded thru the apertures 29 and drawn tightly into the notches 27. For further security the wires may be soldered to the blades, if desired. The pronged ends of the blades, together with the attached wire ends, are then forced into the blade pockets, the elastic pocket walls expanding to accommodate the prongs and the wires and tightly gripping the blades and wire ends to effect a secure and permanent assembly.

If desired, the prongs of each blade may be bent to extend in opposite directions, or both prongs may be bent outwardly rather than inwardly. Also, the uninsulated end portions of the wires may extend first thru the blade notches and thence thru the apertures 29, all such modifications being within my present contemplation.

When coupled in a standard convenience outlet or receptacle, the inwardly toed end portions of the blades are presented in the socket openings and engage against the margins of the outer walls thereof. Then, as the blades are pushed into the sockets, their contacting portions are wedged toward each other as they are caused to slide against the outer socket walls or the adjacent contacts 32, the blades pivoting and their pocketed portions being forced outwardly against the yielding resistance of the pocket walls until they are drawn into substantial parallelism, as shown in Figure 4.

So long as the plug remains in coupled relation, the walls of the blade pockets will be held in a distorted condition against their inherent resilience and will press inwardly against the blades, urging the contacting blade portions outwardly against the contact elements of the outlet or receptacle, thereby obtaining a tight mechanical coupling and good electrical connection. Upon being uncoupled, the blades of the plug are immediately forced to resume their normal angular disposition relative to the housing and the plug may be recoupled and uncoupled a large and indeterminate number of times.

Having thus described my invention, I claim:

1. An attachment plug comprising a housing of elastic and resilient insulating material having blade pockets formed therein extending convergently inward from its face, the face of said housing being otherwise closed and continuous, flat, rigid contact blades carried in said pockets and projecting outwardly therefrom at divergent

angles, the outer end portions of said blades being bent at reverse angles and normally spaced apart a distance such that they are positioned to engage margins of respective socket openings in a standard outlet to cause the blades to be drawn into substantial alignment against the yielding resistance of said housing in the act of coupling the plug in the outlet, said housing having a passage formed therein extending inwardly from the top thereof, wires extending into said passage, branch passages formed in the housing communicating between the lower end of said passage and each of said blade pockets, one of said wires extending thru each of said branch passages and connected to one of said blades within the housing.

2. An attachment plug comprising a one-piece housing of elastic and resilient insulating material, flat, rigid contact blades carried by the housing and projecting outwardly therefrom, the outwardly projecting portions of the blades being disposed at angles to each other and their outer end portions being bent at reverse angles and normally spaced apart a distance such that they are positioned to engage margins of respective socket openings in a standard outlet to cause the blades to be drawn into substantial alignment against the yielding resistance of said housing in the act of coupling the blades in the outlet, said housing having wire passages therein communicating with the inner portions of said blades, and wires extending into the housing thru said passages, one of said wires being connected to each of said blades within the housing.

3. An attachment plug comprising a housing of elastic resilient insulating material, a pair of flat, rigid contact blades carried by the housing and extending outwardly therefrom at divergent angles to each other, the outer end portions of the blades being bent at reverse angles and spaced apart a distance such that they are positioned to engage the outer margins of respective socket openings in a standard outlet, whereby when coupled in the outlet the blades will be drawn into substantial alignment against the yielding resistance of said housing, and means for connecting the wires of an extension cord to the portions of the blades carried within the housing.

4. An attachment plug comprising a resilient and distortable rubber housing having blade pockets formed therein and wire passages therein communicating with the pockets, said pockets extending inward at convergent angles to each other, wires extending thru said passages, and contact blades carried in said pockets and projecting therefrom at divergent angles to each other, said blades having their outer ends spaced apart a distance corresponding to the spacing between socket openings in a standard current supply outlet, said blades each comprising a strip of stiff metal having its inner end bifurcate and transversely bent to form prongs for engaging a wall of the blade pocket, one of said wires extending into each of said pockets and wedged and compressed between the bifurcated portions of the blade.

ALBERT E. GRANT.
